Primary Examiner — Mojtaba Tehrani*(74) Attorney, Agent, or Firm* — Laabs Intellectual Property, LLC(57) **CLAIM**

The ornamental design for a firearm hammer, as shown and described.

DESCRIPTION

FIG. 1 is a lower-back angled view of the firearm hammer, showing the new design.

FIG. 2 is a front view thereof.

FIG. 3 is a back view thereof.

FIG. 4 is a right-side view thereof.

FIG. 5 is a left-side view thereof.

FIG. 6 is a top view thereof; and,

FIG. 7 is a bottom view thereof.

The broken lines in the figures depict unclaimed portions of the firearm hammer only and form no part of the claimed design.
